UNITED STATES PATENT OFFICE

2,583,536

STORAGE TANK

John W. Allen, Chicago, Ill., assignor to Chicago Bridge & Iron Company, a corporation of Illinois

Application November 3, 1945, Serial No. 626,585

1 Claim. (Cl. 48—178)

1

This invention relates to a storage tank, and particularly to a storage tank that is expansible to accommodate varying quantities of liquid or gas.

Many of the storage tanks used for storing liquid or gaseous products have movable covers with a seal to retain the product within the holder. I have invented an improved type storage tank that uses telescoping sections with substantially every section movable with relation to the other sections.

The new storage tank comprises a series of hollow members of different and increasing lateral dimensions, from the smallest to the largest, with all the members arranged about a common axis in the order of their dimensions. Flexible sealing members are provided, with one sealing member between each adjacent pair of hollow members and attached to the hollow members so as to permit relative axial movement therebetween. The sealing members, which are preferably made of fabric impregnated with a gas-impervious flexible material, have edge backings comprising the outer surface of one hollow member and the inner surface of the next largest hollow member, with the intermediate portion of each sealing member being bowed outward by pressure of the contents. All of the hollow members are open at both ends except for closure members across those two hollow members forming the ends of the storage tank.

The invention will be described as related to the embodiments shown in the accompanying drawings. Of the drawings, Fig. 1 is a plan view of an embodiment of the invention with portions broken away; Fig. 2 is a vertical section through the center of the liquid holder of Fig. 1 with the holder substantially empty of liquid; Fig. 3 is a vertical section similar to Fig. 2 with the holder substantially full of liquid; Fig. 4 is a vertical section substantially through the center of an alternate embodiment of the invention with the liquid holder in expanded position; Fig. 5 is a vertical section similar to Fig. 4 showing the holder empty; Fig. 6 is a vertical section of a second alternate embodiment with the liquid holder substantially empty of liquid; Fig. 7 is a vertical section through a gas holder embodying the invention; and Fig. 8 is a view of an alternate type of gas holder.

In the embodiment shown in Figs. 1, 2 and 3, the liquid holder comprises a top cylindrical section 10, a middle cylindrical section 11, and a bottom cylindrical section 12. These sections are all arranged in order of their diameters with

2

the largest section 10 on the outside and the smallest section 12 on the inside (Fig. 2). Each pair of adjacent cylindrical sections have a flexible sealing member 13 between them. These sealing members are preferably made of a fabric impregnated with a flexible impervious material, such as a synthetic rubber. Each sealing member 13 has one end attached to the end of one cylindrical section on the outside surface thereof and the other end attached to substantially the middle of the next largest cylindrical section on the inside surface of said section. Each attached end of the sealing member rests flat against its corresponding surface of the cylindrical section and the attached ends extend in the same direction. This provides a smooth curve over the entire surface of the sealing member with all except the intermediate bowed portion having backing reinforcements comprising the sides of the cylindrical sections. Although as shown the circle of attachment of that end of the sealing member which is attached to the inside surface of the cylinder is shown at substantially the middle of the cylinder, this circle of attachment may be raised or lowered, depending upon the desired capacity of the gas holder. It is preferred that this circle of attachment be not much below the center of the cylindrical section in order that the sealing member may have adequate backing at all times.

The top cylindrical section 10 is provided with a rigid cover 14, while the bottom closure member is in the form of a cylindrical section 15 resting on foundation 16. The base section 15 does not move but serves only as a bottom closure member. The bottom sealing member 13 is attached to this base section 15 at the top edge, and the side of the cylinder 15 serves as a backing for the sealing member. A liquid supply pipe 17 communicates with the interior of the holder and extends through the foundation 16 and up through the base cylindrical section 15.

In order to limit the axial movement of the cylindrical sections 10, 11, and 12, and to prevent undue strain on the sealing members, there are provided spaced chains 18, 19, and 20 around the holder. These spaced chains connect each pair of adjacent cylindrical sections. On the bottom of the movable cylindrical sections 10, 11, and 12 there are provided annular horizontal flanges 21, 22, and 23 extending outwardly. Flange 21 is on the bottom of cylindrical section 10, flange 22 is on the bottom of cylindrical section 11, and flange 23 is on the bottom of cylindrical section 12. Spaced chains 18 extend from

the foundation 18 to the bottom edge of cylindrical section 12. Spaced chains 19 extend from flange 23 to the bottom of cylindrical section 11, and chains 20 extend from the flange 22 to the bottom of cylindrical section 10. These flanges serve not only as points of attachment for the spaced chains, but also serve to hold the movable cylindrical sections 10, 11, and 12 apart when the holder is substantially empty as shown in Fig. 2.

In order to limit the over-all expansion of the gas holder to a predetermined maximum, a long chain 24 is provided hanging centrally within the gas holder. This chain is attached at one end to the bottom surface of the tank and at the other end to the cover 14. The top end of the chain 24 is operatively attached to a valve 25 for venting when the maximum expansion of the tank has been reached. This valve may be of any of the ordinary type which is opened by the pull of chain 24.

In the embodiments shown in Figs. 4 and 5 the order of the cylindrical sections is reversed with the cylindrical section 15a being at the top of the holder and the largest cylindrical section 10a being at the bottom. Corresponding sealing members 13, chains 19 and 20, and flanges 21, 22, and 23 are provided. An additional flange 26 is provided at the roof edge of cylinder 15a. There is also provided the long central chain 24 and the valve 25 together with the supply pipe 17.

In the liquid holder shown in Figs. 4, 5 and 6 there is provided a central open top cylinder 27 resting on the bottom of the holder with the bottom end of chain 24 extending into the cylinder. There are also provided roof reinforcements 28.

The holders shown in Figs. 7 and 8 are for the storage of gases. In Fig. 7 there are provided cylinders 10b, 11b, 12b, and 15b and sealing members 13 between adjacent cylinders. Chains 20b are provided to limit expansion of the holder. There is also provided a stabilizing device comprising a central well 29 attached to the roof and housing a weight 30. This weight is attached by means of radial cables 31 to the top of the bottom cylinder 10b. Each cable runs over a sheave 32 attached to the top of the well 29, over a second sheave 33 attached to the top edge of cylinder 15b, over a third sheave 34 attached to the middle of cylinder 15b, over a fourth sheave 35 attached to the top of cylinder 12b, over a fifth sheave 36 attached to the middle of cylinder 12b, over a sixth sheave 37 at the top of cylinder 11b, over a seventh sheave 38 at the middle of cylinder 11b, and up to the top 39 of cylinder 10b. Each cable 31 passes through holes 40 provided in the top of the well 29. The well is provided with a cover 41.

In the embodiment shown in Fig. 8 there are the cylinders 10c, 11c, 12c and 15c sealing members 13, valve 25, central chain 24, and side stabilizing chains 18c and 20c. There is also provided a stabilizing apparatus comprising wheels 42 vertically aligned and rolling against columns 43. As many sets of wheels 42 and columns 43 may be provided as desired. Additional wheels 44 are

provided mounted on the bottom of top cylinder 10c and contacting second cylinder 11c. Other wheels 45 are provided mounted on the bottom of cylinder 11c and contacting third cylinder 12c. 5 Ordinary bracing 46 is provided between the columns 43.

In the case of gas holders, the flexible sealing members resist only gas pressure while with liquid holders the members resist only liquid pressure. However, they can also be made to resist a combination of gas and liquid pressure.

In all embodiments of the invention the sealing members 13 are attached in the same manner and expansion of the tanks is limited to a predetermined maximum.

When filling the tanks the top cylindrical section will rise first to the limit of its spaced chains, and then the other sections will follow in order. When the tank is emptied the bottom section will come to rest on the base of the structure first, followed by the others in regular order.

Having described my invention as related to a typical embodiment of the same, it is my intention that the invention be not limited by any of 25 the details of description but rather be construed broadly within its spirit and scope as set out in the accompanying claim.

I claim:

An expandable storage tank comprising a series 30 of cylindrical metal sections of different diameters substantially arranged about a common axis in the order of their diameters and flexible sealing members between the cylindrical sections with each sealing member connecting one cylindrical section to the next larger so as to permit relative axial movement therebetween with the bottom of each metal section, except the lowermost section, rising no higher than the top of the next lower section when the tank is fully expanded axially, 35 said cylindrical sections being open at both ends except for closure members extending across those two sections forming the top and bottom ends of the storage tank, and stabilizing means for the tank including a well in the top closure, a movable weight in the well, a plurality of flexible cables having one end attached to the weight and having the other end attached to the bottom cylindrical section, the intermediate portion of the cable passing over sheaves attached to each 40 of the cylindrical sections.

JOHN W. ALLEN.
